**6-CHLORO-1,2 α -METHYLENE- Δ^6 -17 α -HYDROXY-
PROGESTERONE COMPOUNDS AND COM-
POSITIONS**

1. **POSTION**
Rudolf Wiechert, Berlin-Lichterfelde, Germany, assignor
to Schering Aktiengesellschaft, Berlin, Germany
No Drawing. Filed Apr. 24, 1962, Ser. No. 189,724
Claims priority, application Germany, Apr. 29, 1961,
Sch 29,643

Serial No. 29,945
The portion of the term of the patent subsequent to
Mar. 31, 1981, has been disclaimed
12 Claims (Cl. 167—74)

The present invention relates to new progestational agents and treatments therewith, and more particularly to new 6-position halogenated $1,2\alpha$ -methylene- Δ^6 - 17α -hydroxyprogesterones which have an unusually high progestational action, even upon peroral administration, to these new compounds, methods of producing the same, progestational compositions containing the same, and progestational treatments using these compounds.

It is a primary object of the present invention to provide a new series of compounds with progestational activity.

It is another object of the present invention to provide 6-position halogenated 1,2 α -methylene- Δ^6 -17 α -hydroxy-progesterone esters which have a remarkably high progestational activity.

It is yet another object of the present invention to provide for the production of these new compounds.

The present invention also has as its object the provision of progestational compositions containing the compounds of the present invention as the active ingredient thereof, and also the treatment of patients requiring progestational effect.

Other objects and advantages of the present invention will be apparent from a further reading of the specification and of the appended claims.

With the above and other objects in view, the present invention mainly comprises a compound of the formula:

wherein X is a halogen, and wherein R is selected from the group consisting of hydrogen and acyl wherein acyl is derived from a carboxylic acid.

The esters of the present invention, i.e., compounds of the above formula wherein R is acyl derived from a carboxylic acid, have been found to have a surprisingly high degree of progestational action, which is in many cases equal to and superior to the progestational action of known compounds used for this purpose, and particularly upon peroral administration is in many cases several times greater than the progestational action of known compounds used for this purpose. Accordingly, the most preferred progestational compounds of the present invention are the 6-position halogenated-1,2 α -methylene-

2

Δ^6 -17 α -hydroxyprogesterone esters of carboxylic acids.

Although the invention is in general applicable to all 6-halogenated compounds of the above group, it is most preferred from the point of view of high progestational action that the halogen in the 6-position be chlorine. Thus, for example, although the 6-brominated compounds are also active progestational compounds, the action thereof is considerably less than the 6-chlorinated corresponding compounds.

10 The present invention is in general applicable to all types of carboxylic acid esters of 6-halogen-1,2 α -methylene- Δ^6 -17 α -hydroxyprogesterone, including aliphatic acid esters, alicyclic acid esters, aromatic acid esters and mixed open chain-cyclic carboxylic acid esters. All of these 15 esters may be produced in analogous manner to the production of the esters of the present invention which will be shown in the examples given below.

The preferred esters from the point of view of the progestational activity of the present invention are the aliphatic carboxylic acid esters of up to 10 carbon atoms, such as the acetate, propionate, valerate, capronate, enanthate, etc. The acetate exhibits a particularly high degree of progestational activity, particularly upon peroral administration, and the higher homologous esters exhibit a similar high degree of progestational activity, which, particularly in the case of peroral administration, is higher than that of known progestational compounds. In the case of the higher homologs, starting with the enanthate, there is in addition a valuable protraction of the progestational activity. Also preferred for the purposes of the present invention are the alicyclic and mixed open chain-cyclic carboxylic acid esters, such as the cyclopentylpropionate.

The compounds of the present invention may be incorporated into progestational compositions of all type, e.g., for injection purposes, such as by subcutaneous injection, or for peroral administration. Although it is a particular advantage of the present invention that the compounds thereof have a highly superior progestational activity upon peroral administration, it is apparent that this invention should not be limited to the use of the compounds for peroral administration because the compounds can also be used by injection, by per os administration, for example in the form of suppositories, etc.

45 For example, in the form of suppositories, etc.

45 In preparing compositions with the progestational compounds of the present invention, these compounds can be used as active ingredient with any normal pharmaceutical carrier or excipient for administration by injection, for peroral administration in the form of tablets, dragees, 50 emulsions, for rectal administration suppositories, etc. Thus, for example, in the manufacture of tablets and dragees the pharmaceutical carriers and excipients would include diluents and absorbents such as amidone, sugar, carbonates, kaolin, etc.; agglutinants such as carboxy-methyl cellulose, alginates, gums, sorbitol, polyvinyl-pyrrolidone, pectins, etc.; lubricants such as talc, stearic acid, stearates, etc.; wetting agents such as sorbitan, mono-oleate, oleates or stearates of triethanolamine, etc.; buffering substances such as calcium salts, glycocols, magnesium trisilicate, etc.; coating substances such as gluten, cellulose acetophthalate, methyl phthalate, ethyl phthalate, etc.; carriers and excipients for emulsions, such as poly-ethylene-glycol, carboxymethyl cellulose, methyl cellulose, sorbitan mono-oleate, interesterified oils, etc.; and 60 carriers and excipients for suppositories such as cocoa butter, synthetic semi-glycerides, etc.

As indicated above, a particular advantage of the

present invention is that the composition thereof can be administered in the form of capsules, tablets, dragees, or in the form of a liquid containing the active ingredient, and upon oral administration a high degree progestational effect is achieved.

The daily dose of the progestational agents of the present invention is between about 1 mg. and 6 mg. per day, this amount being given either in a single dose or in divided doses. The preferred daily dose of the progestational agents of the present invention is generally about 3 mg. per day.

The compounds of the present invention are produced by introducing a halogen atom into the 6-position of the chosen 1,2 α -methylene- Δ^6 -17 α -hydroxyprogesterone ester. In accordance with the method of the present invention the 1,2 α -methylene- Δ^6 -17 α -hydroxyprogesterone ester is first converted in known manner, preferably by means of percarboxylic acids, particularly perbenzoic acid, into the corresponding 6,7 α -epoxide, which is then treated with the hydrohalic acid, preferably in glacial acetic acid solution, whereby in a single operation the cyclopropane ring is opened with the formation of a 1 α -halogen methyl group, and the epoxy ring is opened with the splitting-off of water and the formation of the 6-halogen- Δ^6 grouping. The 1 α -halogen methyl group of the reaction product is then subsequently re-converted into the 1,2 α -methylene group, preferably by means of organic bases, particularly collidine. This method is illustrated by the following general equations:

wherein R and X have the same definitions as above.

The starting compounds for the method of the present invention may be produced in accordance with the methods shown in German Patent No. 1,072,991, German Patent No. 1,096,353, and U.S. patent application Serial No. 60,812, now U.S. 3,127,396 filed October 6, 1960, for "Production of 1,2-Methylene and 16,17-Methylene Ketosteroids."

The surprisingly strong progestational action, particularly upon peroral administration, of the compounds of the present invention is illustrated by the following comparative tests wherein 6-chloro-1,2 α -methylene- Δ^6 -17 α -hydroxyprogesterone-acetate was compared with compounds known to have a very strong progestational action. In these tests there was determined the minimum amount of the tested compound sufficient to achieve an adequate positive Clauberg test on infantile rabbits. The results are summarized in the table below, and show the

marked superior activity of the compound of the present invention:

Compound	Necessary dose in mg. upon administration	
	Subcutaneous	Peroral
6-chloro-1,2 α -methylene- Δ^6 -17 α -hydroxyprogesterone-acetate	0.003	0.01
19-nor-17 α -hydroxy-progesterone-acetate	0.003	0.1
17 α -Hydroxy-progesterone-acetate	0.03	0.9
19-nor-17 α -ethinyl-testosterone	0.06	0.1
19-nor-17 α -ethinyl-testosterone-acetate	0.03	0.03

The following examples are given to further illustrate the present invention. The scope of the invention is not, however, meant to be limited to the specific details of the examples.

Example 1

2.34 g. of 1,2 α -methylene- $\Delta^4,6$ -pregnadiene-17 α -ol-3,20-dione-17-acetate are dissolved in 18.25 cc. of ethylene chloride which contains 844 mg. of perbenzoic acid. The solution is stored for 16 hours at +5°C. and 7 hours at room temperature. It is then diluted with methylene chloride and, with aqueous ferrous sulfate solution, sodium bicarbonate solution and with water washed into neutral.

The organic phase is dried over sodium sulfate and then concentrated to dryness. 1.62 g. of the thus obtained crude 1,2 α -methylene-6,7 α -oxido- Δ^4 -pregnene-17 α -ol-3,20-dione-17-acetate are dissolved in 109 cc. of glacial acetic acid. This solution is then saturated at room temperature with hydrogen chloride gas and stored for 20 hours. It is then diluted with methylene chloride and washed with water until neutral.

The organic phase is dried over sodium sulfate and then concentrated to dryness. The thus obtained crude 6-chloro-1 α -chloromethyl- $\Delta^4,6$ -pregnadiene-17 α -ol-3,20-dione-17-acetate is heated to boiling in 20 cc. of collidine for 20 minutes under nitrogen. After dilution with ether it is washed with 4 normal hydrochloric acid and washed with water until neutral.

After drying over sodium sulfate and concentration to vacuum the remaining residue is subjected to chromatography over silica gel. Using a benzene-ethyl acetate mixture (19:1) there is eluted 900 mg. of 6-chloro-1,2 α -methylene- $\Delta^4,6$ -pregnadiene-17 α -ol-3,20-dione-17-acetate, which upon recrystallization from isopropyl ether melts at 200-201°C.

UV: $\epsilon_{281} = 17820$ (Methanol).

Example 2

8.7 g. of 1,2 α -methylene- $\Delta^4,6$ -pregnadiene-17 α -ol-3,20-dione-17-capronate (produced according to the methods of German Patent No. 1,072,991 and German Patent No. 1,096,353) and 2.77 g. of perbenzoic acid in 52.9 cc. of ethylene chloride are allowed to stand for 17 hours at 5°C. and 7 hours at room temperature. The reaction mixture is then further worked up as described in Example 1 and the obtained crude 1,2 α -methylene-6,7 α -oxido- Δ^4 -pregnene-17 α -ol-3,20-dione-17-capronate are dissolved in 585 cc. of glacial acetic acid.

The solution is saturated with hydrogen chloride gas at room temperature and allowed to stand for 20 hours. It is then diluted with methylene chloride and washed with water until neutral.

The organic phase is dried over sodium sulfate and concentrated to dryness. There is thus obtained 9.4 g. of crude 6-chloro-1 α -chloromethyl- $\Delta^4,6$ -pregnadiene-17 α -ol-3,20-dione-17-capronate which is dissolved in 87 cc. of freshly distilled collidine and heated under refluxing and under nitrogen for 30 minutes. The reaction mixture is then further worked up and subjected to chromatography as described in Example 1.

There is thus obtained 3.1 g. of 6-chloro-1,2 α -methyl-
ene- $\Delta^{4,6}$ -pregnadiene-17 α -ol-3,20-dione-17-capronate as an
oil.
UV: $\epsilon_{282}=17500$.

Analysis.—Chlorine: 7.5 calculated. 7.4 found. 5

Example 3

This example describes the production of tablets.
1 g. of 1,2 α -methylene-6-chloro- Δ^6 -17 α -hydroxypro-
gestrone-17-acetate are granulated in normal manner with 10
36 g. of lactose, 25.6 g. of corn starch and with 1.4 g.
of gelatin with the addition of 0.035 g. of peroxy-benzoic
acid methyl ester/propylester, and after the addition of
6 g. of talcum pressed into tablets in the usual manner,
each tablet weighing about 120 mg. and containing about
1 mg. of the active ingredient.

Example 4

970 mg. of 1,2 α -methylene- $\Delta^{4,6}$ -pregnadiene-17 α -ol-3,
20-dione-17-propionate (M.P. 192.5-195.5°) [produced
according to the methods of German Patent No. 1,072,991
and German Patent No. 1,096,353] are treated with
perbenzoic acid as described in Example 2 and worked
up. After recrystallisation from ethylacetate 538 mg.
1,2 α - methylene - 6 α - oxido - Δ^4 - pregnene - 17 α - ol-
3,20-dione-17-propionate (M.P. 199-202°) are obtained
and reacted in the same manner as described in Exam-
ple 2.

There is thus obtained 120 mg. 6-chloro-1,2 α -methyl-
ene - $\Delta^{4,6}$ - pregnadiene - 17 α - ol - 3,20 - dione - 17 - pro-
pionate melting at 190.5-191.5° C.

UV: $\epsilon_{284}=17500$.

Example 5

5 g. 1,2 α -methylene- $\Delta^{4,6}$ -pregnadiene-17 α -ol-3,20-dione-
17-valerate [produced according to the methods of Ger-
man Patent No. 1,072,991 and German Patent No.
1,096,353] are reacted in the same manner as described
in Example 1. After chromatography over silica gel 2 g. 40
6 - chlor - 1,2 α - methylene - $\Delta^{4,6}$ - pregnadiene - 17 α -ol-
3,20-dione-17-valerate are obtained as an oil.

UV: $\epsilon_{282}=17600$.

Example 6

5 g. 1,2 α -methylene- $\Delta^{4,6}$ -pregnadiene-17 α -ol-3,20-dione-
17-cyclopentylpropionate [produced according to the
methods of German Patent No. 1,072,991 and German
Patent No. 1,096,353] are reacted in the same manner
as described in Example 1. After chromatography over
silica gel 1.8 g. 6-chlor-1,2 α -methylene- $\Delta^{4,6}$ -pregnadiene-
17 α -ol-3,20-dione-17-cyclopentylpropionate are obtained
as an oil.

UV: $\epsilon_{282}=17100$.

Without further analysis, the foregoing will so fully
reveal the gist of the present invention that others can
by applying current knowledge readily adapt it for vari-
ous applications without omitting features that, from the
standpoint of prior art, fairly constitute essential char-
acteristics of the generic or specific aspects of this in-
vention and, therefore, such adaptations should and are
intended to be comprehended within the meaning and
range of equivalence of the following claims.

I claim:

1. A compound of the formula:

- 15 wherein X is chlorine; and wherein R is selected from the group consisting of hydrogen and acyl wherein acyl is derived from a hydrocarbon aliphatic carboxylic acid of up to 10 carbon atoms.
2. The up to 10 carbon atom hydrocarbon aliphatic 20 carboxylic acid ester of 6-chloro-1,2 α -methylene- Δ^6 -17 α -hydroxyprogesterone.
3. The 6 - chloro - 1,2 α - methylene - Δ^6 - 17 α - hydroxyprogesterone ester of a hydrocarbon alicyclic carboxylic acid of up to 10 carbon atoms.
- 25 4. The compound 6-chloro-1,2 α -methylene- Δ^6 -17 α -hydroxyprogesterone-acetate.
5. The compound 6-chloro-1,2 α -methylene- Δ^6 -17 α -hydroxyprogesterone-capronate.
- 30 6. The compound 6-chloro-1,2 α -methylene- Δ^6 -17 α -hydroxyprogesterone-propionate.
7. The compound 6-chloro-1,2 α -methylene- Δ^6 -17 α -hydroxyprogesterone-valerate.
8. The compound 6-chloro-1,2 α -methylene- Δ^6 -17 α -hydroxyprogesterone-cyclopentylpropionate.
- 35 9. A progestational composition in daily dose form, comprising between about 1 mg. and 6 mg. of the 6-chloro-1,2 α -methylene- Δ^6 -17 α -hydroxyprogesterone ester of a hydrocarbon aliphatic carboxylic acid of up to 10 carbon atoms as active ingredient; and a pharmaceutical carrier.
10. A progestational composition in daily dose form, comprising between about 1 mg. and 6 mg. of 6-chloro-1,2 α -methylene- Δ^6 -17 α -hydroxyprogesterone-acetate in an amount sufficient to achieve a progestational effect as active ingredient; and a pharmaceutical carrier.
- 45 11. A progestational composition in daily dose form, comprising between about 1 mg. and 6 mg. of 6-chloro-1,2 α -methylene- Δ^6 -17 α -hydroxyprogesterone-capronate in an amount sufficient to achieve a progestational effect as active ingredient; and a pharmaceutical carrier.
- 50 12. A progestational composition in daily dose form for peroral administration, comprising between about 1 mg. and 6 mg. of the 6-chloro-1,2 α -methylene- Δ^6 -17 α -hydroxyprogesterone ester of a hydrocarbon aliphatic carboxylic acid of up to 10 carbon atoms as active ingredient in an amount sufficient to achieve a progestational effect; and a pharmaceutical carrier adapted for peroral administration.
